[57] CLAIM

The ornamental design for a folding knife, as shown and described.

DESCRIPTION

FIG. 1 is a perspective view of a folding knife, showing our new design, illustrated with the blade in a closed position;

FIG. 2 is front view thereof in elevation;

FIG. 3 is a right side elevational view thereof, the left side view being a mirror image thereof;

FIG. 4 is a rear view thereof in elevation;

FIG. 5 is a top plan view thereof;

FIG. 6 is a bottom plan view thereof;

FIG. 7 is a perspective view thereof, illustrated with the blade in an extended position;

FIG. 8 is a front elevational view of FIG. 7;

FIG. 9 is a right side elevational view of FIG. 7, the left side view being a mirror image thereof;

FIG. 10 is a rear elevational view of FIG. 7;

FIG. 11 is a top plan view of FIG. 7; and,

FIG. 12 is a bottom plan view of FIG. 7.
